George E. Lint,
BY E. B. Stocking, Attorney

UNITED STATES PATENT OFFICE.

GEORGE E. LINT, OF YORK, PENNSYLVANIA.

WINDOW-SASH HOLDER.

SPECIFICATION forming part of Letters Patent No. 658,954, dated October 2, 1900.

Application filed June 27, 1900. Serial No. 21,831. (No model.)

To all whom it may concern:

Be it known that I, GEORGE E. LINT, a citizen of the United States, residing at York, in the county of York, State of Pennsylvania, have invented certain new and useful Improvements in Window - Sash Holders, of which the following is a specification, reference being had therein to the accompanying drawings.

10 This invention relates to window-sash holders, and particularly to improvements upon the wedge-strip and spring-bead shown and described in my Patent No. 651,465, granted June 12, 1900.

15 The invention has for an object to improve the construction of the wedge-strip so that the same may be drawn toward the sash and permit the free movement of the window whenever desired, whereby the sticking of 20 the sash in its lowered position can be prevented and the spring for operating the strip placed under compression.

A further object of the invention is to provide means for retaining in position and adjusting the amount of movement of the free 25 end of the spring-bead which is adapted to bear against a shoulder upon the sash at the opposite side from the wedge-strip, and thus produce an equal pressure upon the sash, causing 30 it to travel in a straight line.

Other objects and advantages of the invention will hereinafter appear in the following description, and the novel features thereof will be particularly pointed out in the appended claims.

35 In the drawings, Figure 1 is an elevation of a window-frame having the invention applied thereto, with parts in section and broken away. Fig. 2 is a vertical longitudinal section of one side of a sash containing the improved wedge-strip. Fig. 3 is a horizontal section on the line 3 3 of Fig. 1, and Fig. 4 is a detail vertical section of the upper portion of the spring-pressed bead.

40 Like letters of reference indicate like parts throughout the several figures of the drawings.

The letter A designates a window-frame which may be supplied with any usual form 45 of sashes B, either or both of which may be supplied with the improved devices constituting the present invention. For the pur-

pose of illustration I have shown the wedge-strip C as applied to the lower sash B and provided with a flange C', extended into a groove B' in the sash. This forms a compact joint between the sash and wedge-strip, which prevents the entrance of air or insects between the strip C and the edge of the sash B, while the flange is completely concealed from view and offers no obstruction to the operation of the sash, nor does it affect the usual appearance thereof. This strip C is provided at its lower portion with an angular pivot C², seated in a socket B², as described in my former patent, and also supplied with a spring C³, disposed in a socket B³ of the sash and operating to normally force the strip away from the edge of the sash B. The operation of these parts is not more fully described, as it is clearly set forth in the former patent. For the purpose of relieving this spring-pressure of the strip C against the way A' of the frame I have provided a retracting device for the strip of very simple construction and adapted to be operated by means upon the sash. This device constitutes a flexible connection D, secured at one end to the strip C and at the opposite end to a spindle or shaft D', journaled in the sash and disposed within a recess D² thereof. This spindle D' is provided with any desired form of operating-handle D³, and it will be noted that the flexible connection between the spindle and strip permits the free movement of the strip toward and from the sash without affecting the connection between the strip and the retracting device. If the sash be in the lowered position (shown in Fig. 1) and it be desired to raise the same easily, the handle D³ is turned so as to wind the flexible connection D upon the spindle D', thus drawing the strip toward the sash and relieving the way A' of the frictional contact with the strip. The window may thus be readily raised or lowered.

At the opposite side of the sash from the wedge-strip C the spring-pressed bead E is provided and adapted to bear against a shoulder B⁴ upon the sash. This bead is forced outward by any suitable construction or arrangement of spring, and in my former patent the outward movement of the end of the bead beyond the sash was limited by a pin or

lug carried by the other sash. For the purpose of limiting and adjusting the extent of movement of this bead E, I have devised a holding means, which consists of a pin F, 5 adapted to be adjusted in the window-frame by any desired means—for instance, threads F' upon its point—and provided with a head F², adapted to contact with the outer face of the bead E to limit the movement thereof. 10 This bead may be provided with any desired form of sleeve E² around the pin F, or the aperture thereon may be made of sufficient size to permit of a free movement. It will thus be seen that the extent of movement 15 and the consequent degree of pressure upon the shoulder of the sash may be readily limited by adjusting the pin F, and this will also govern and control the raising of the sash when the wedge-strip is retracted, as the extent of movement of the bead E will be so limited that when the wedge C is retracted no tension will be exerted upon the shoulder of the sash and the same left free for movement in raising or lowering. If, owing to 20 shrinkage or other reasons, the sash becomes loose in the frame, the pin F may be adjusted so as to obtain the desired contact-pressure against the sash to hold the same against any rattling or other movement. The construction 25 of retracting device herein employed embodying the flexible connection with the strip is particularly desirable, owing to the simplicity of construction and as it permits a movement of the strip in the operation of the window independent of the operation of the spindle, so that no damage or disarrangement of the retracting parts will occur if the sash be operated without using the retracted device. 30 It will be obvious that changes may be made in the details of construction and configuration without departing from the spirit of the invention as defined by the appended claims. 35 Having described my invention, what I

claim as new, and desire to secure by Letters Patent, is—

1. In a window-sash holder, the combination with a frame, of a sash provided with a strip disposed between the sash and frame, a spring for forcing said strip away from said sash, a spindle mounted in said sash, and a flexible connection between said spindle and strip; substantially as specified. 50

2. In a window-sash holder, the combination with the frame having a way, of a sash provided with a wedge-strip having its lower end in contact with a sash, a spring for forcing the upper end of said strip away therefrom, a spindle rotatably mounted in said sash, and a flexible connection extending from said spindle to said strip; substantially as specified. 60

3. In a window-sash holder, the combination with a frame having a way, of a sash provided with a spring-pressed wedge-strip pivoted at one end, a shoulder upon said sash at the opposite side of said strip, a bead bearing against said shoulder, and a headed pin extending through an aperture in said bead and adjustably secured to said frame; substantially as specified. 65

4. In a window-sash holder, the combination with a frame having a way, of a sash provided with a wedge-strip pivoted at its lower portion in said sash, a spring to force said strip against said way, a spindle rotatably mounted in said sash, a flexible connection between said strip and spindle, a yielding bead bearing against a shoulder upon said sash upon the opposite side from said strip, and a headed pin extending through the aperture in said bead and adjustably secured to said frame; substantially as specified. 70 80

In testimony whereof I affix my signature 85 in presence of two witnesses.

GEORGE E. LINT.
